CLAIM

The ornamental design for a vehicle headlight as shown and described.

DESCRIPTION

FIG. 1 is a right side view of a first embodiment a vehicle headlight showing the present design;

FIG. 2 is a front and right side perspective view thereof;

FIG. 3 is a front view thereof;

FIG. 4 is a front, top and right side perspective view thereof;

FIG. 5 is a left side view of a second embodiment of a vehicle headlight showing the present design, the second embodiment being a mirror image of the first embodiment;

FIG. 6 is a front and left side perspective view thereof, being a mirror image of FIG. 2;

FIG. 7 is a front view thereof, being a mirror image of FIG. 3; and,

FIG. 8 is a front, top and left side perspective view thereof, being a mirror image of FIG. 4.

The features shown in halftone or ghosted manner surrounded by broken lines form no part of the claimed design.

The “I.Q.LIGHT” forming part of the claimed design is a registered trademark of Volkswagen Aktiengesellschaft.

1 Claim, 8 Drawing Sheets
